UNITED STATES PATENT OFFICE.

EDWIN V. WHITAKER, OF GLOVERSVILLE, NEW YORK.

IMPROVEMENT IN GLOVES.

Specification forming part of Letters Patent No. 122,091, dated December 19, 1871.

To all whom it may concern:

Be it known that I, EDWIN V. WHITAKER, of Gloversville, in the county of Fulton and State of New York, have invented a new and useful Improvement in Gloves; and I do hereby declare that the following is a full, clear, and exact description thereof, which will enable others skilled in the art to make and use the same, reference being had to the accompanying drawing forming part of this specification, in which—

Figure is a view of back of glove made up; Fig. 2, view of front piece spread out; and Fig. 3, view of back piece spread out. Fig. 4 is a view of the thumb piece spread out.

The object of my invention is to produce a glove having a peculiar curve or swell at the wrist with a minimum waste of material and expenditure of labor in making up. The glove is composed of three parts, and I cut both the palm and back piece as nearly rectangular as possible, and yet with a curve from the fingers backward toward the wrist, so as to impart the requisite shape, as hereinafter described.

Referring to the drawing, *a* is the back piece; *b*, the palm piece; *c*, the laps of the palm piece over the back; *d*, the seams between the palm and back pieces. From the inside of the tips of the first and fourth fingers the seams *d* run straight to the

points *e* without forchettes. I am aware that it is not new to cut the edges of glove pieces without forchettes; but this has not been done, so far as I know, in the case of a glove made in three pieces; and in cutting skins for gloves of the latter class greater economy of stuff can be secured than when each glove is made of a single piece. The flare of the back *a* on each side from *e* to *f* is given so as to make the glove accommodate itself more closely to the shape of the wrist. The form of the thumb piece *h* is clearly shown in Fig. 4. By bringing together and uniting its side edges *i* it is in condition to be united to the palm piece by sewing its base edge *K* to the edge of the opening therein, as shown in Fig. 2.

I desire it to be understood that I lay no claim to a glove made in three parts, nor with an overlapping palm piece; but

I do claim as of my invention—

The glove herein described, having its back and palm pieces *a* and *b* cut with the straight and curved edges, as shown, for the purpose specified.

To the above specification of my invention I have signed my name this 12th day of October, A. D. 1871.

Witnesses: E. V. WHITAKER.
